MOVABLE BED PNEUMATIC STRATIFIER

Azle Herbert Utley, Auburn, Calif.

Application February 27, 1947, Serial No. 731,235

2 Claims. (Cl. 209—466)

1

This invention relates to a dry mineral concentrator.

An object of the invention is the construction of a machine which will operate very efficiently when handling dry material.

Another object of the invention is the construction of a compact, portable machine that will operate highly efficiently in recovering valuable metals from ores.

A still further object of the invention is the construction of a machine in which a novel and efficient vibrating table or classifier is employed.

Another object of the invention is the construction of a machine employing a novel nugget-trap as well as a control valve device; said control valve device being employed for governing the amount of the air passing to the vibrating table or classifier.

Another object is the construction of a machine that can be easily transported, as well as operated by a single person, which machine will produce highly efficient results.

With the foregoing and other objects in view, this invention comprises certain novel constructions, combinations, and arrangements of parts as will be hereinafter fully described, illustrated in the accompanying drawings, and more particularly pointed out in the appended claims.

In the drawings:

Figure 1 is a top plan view of the machine, showing part of the cover broken away.

Figure 2 is an elevated side view of the machine.

Figure 3 is a top plan view of the machine with the cover removed.

Figure 4 is a vertical longitudinal sectional view taken on line 4—4, Figure 3, and looking in the direction of the arrows.

Figure 5 is a transverse sectional view, taken on line 5—5, Figure 4, and looking in the direction of the arrows.

Figure 6 is a transverse sectional view, taken on line 6—6, Figure 4, and looking in the direction of the arrows.

Figure 7 is a transverse sectional view, taken on line 7—7, Figure 4, and looking in the direction of the arrows.

Figure 8 is a transverse sectional view, taken on line 8—8, Figure 4, and looking in the direction of the arrows.

Figure 9 is a fragmentary view in side elevation of the machine, part being shown in sections.

Figure 10 is a fragmentary view in side elevation of the gear casing.

2

Figure 11 is a view in side elevation of the gear to which is fixedly attached the flat spur-carrying ring.

Figure 12 is a longitudinal sectional view of another embodiment of the vibrating table or classifier, while

Figure 13 is a similar view of another embodiment of the classifier.

Figure 14 is a perspective view of the nugget trap.

Referring to the drawings, in which the preferred embodiment of invention is illustrated, 1 designates a housing or casing which has a suitable base 2. The primary casing 1 includes a removable cover 3. A hopper 4 is hingedly mounted at 5 on said cover 3. The hopper 4 extends into the machine as is clearly shown in Figures 4 and 5. A link 6 is pivotally connected at 7 to the hopper while a link 8 is pivotally connected at its lower end to a fixed link 9, the upper end of link 8 being pivotally connected at 10 to link 6. Link 9 is fixedly supported upon the side of the machine 1. The operator can swing the hopper 4 to its forward position as shown in Figures 2 and 4, or he may swing the hopper 4 in the opposite direction. By swinging the hopper 4 the rubber strap 11 can be moved closer to or placed farther away from the vibrating table or classifier 12. This positioning of the lower end of hopper 4 and its rubber strip or strap controls the amount of ore that passes to the vibrating classifier. The rubber strap or strip 11 is secured across the outer face of one side of hopper 4.

The vibrating table or classifier 12 comprises an upper receiving deck 13 which has at its forward end a screen 14; the screen being held in position by metal strips 15 which are secured to the inner faces of the sides 16 of the classifier 12. The classifier 12 has a lower deck 17, which may be known as a table, or the bottom of the classifier. On this deck or bottom 17 is a condenser 18; this condenser comprises a frame with a number of parallel screens for very finely screening the ore coming in contact therewith. The vibrating classifier 12 is mounted at its inner end on link 19, which link is pivotally mounted at 20 upon the side of the primary casing 1. There are two links 19, one at each side of the casing and classifier. A pair of links 21 support the lower or outer end of the classifier 12. These links 21 are pivotally mounted on the housing or casing 1 while their lower ends are pivotally connected to said classifier, Fig. 4. Therefore, the classifier 12 is permitted to reciprocate with

in the casing 1 by reason of being supported by said movable links 19 and 21.

A nugget-trap 22 is held in the lower end of classifier 12 by frictional engagement only. This nugget-trap 22 comprises a metal frame 23 which has a transverse plate 24 that fits under the floor 17 as clearly shown in Fig. 4. The sides of said nugget-trap 22 are notched at 25, so that the inner ends 26 overlap a part of the bottom 17, with the outer edge of said bottom in notches 25, and bearing upon the metal plate 24. The nugget-trap 22 is provided with a central screen division 26; and near its outer end is provided with an upstanding portion 27.

On the base or bottom 2 of the casing 1 is a drawer 28, which is divided by a transverse piece 29. This drawer 28 is placed under the vibrating classifier 12. The casing 1 is provided with a hook-stop 30, Fig. 4, which is adapted to be engaged by the upstanding rubber strip 31 projecting from the top of the drawer 28; this produces not only a stop for preventing the drawer from being shoved too far into the casing, but it acts as a closure means for one end of the compartment of the casing 1 under the vibrating classifier.

To control the amount of air passing into the classifier 12, when the machine is in operation, a valve device 32 is employed. This valve device comprises a shaft-like body 33, Fig. 5, on which is mounted a suitable clip 34 (Figs. 4 and 5) in which clip 34 is secured the lower portion of a piece of flexible material 35. This piece of material 35 may be formed of leather or rubber and is provided to close, if the operator desires, the inner end of the compartment formed between the deck 13 and the bottom 17 of the classifier 12. However, when the operator desires, he can grasp handle 36 and swing the valve device to any desired position so as to permit more or less air to enter the classifier, as he desires. The air is driven rearwardly within the casing 1 by means of the rotary fan or blower 37, Fig. 9. This blower 37 is of the usual type. The shaft-like body 33 is pivotally mounted on casing 1 at one end by means of screw 38, whereas screw or any like means 39 fixedly connects handle 36 with the shaft 33 whereby movement of the handle 36 will positively operate the control valve device 32.

A pair of springs 40 are attached at the inner ends to the sides of the vibrating classifier; while the outer ends of said springs 40 are attached to the inner ends of wire links 41. Wire links 41 are hooked through transverse strip 42, which strip is fastened at its ends to the sides of the casing 1, Fig. 3. Therefore said springs 40 tend to move the classifier towards the discharge end of the machine when the classifier is moved to the right or front end of the machine during the vibration movement of the classifier.

The power shaft 43 is provided outside the casing 1 with a crank handle 44. Within the casing 1 is a gear casing 45 in which is mounted gear 46 (Figs. 8 and 11). This gear 46 is fixedly secured upon the power shaft 43. Fixedly secured to one side of gear 46 is a flat ring 47. Extending from the outer face of the flat ring 47 are a plurality of pins or spurs 48. When the gear 46 is rotated these pins or spurs 48 engage one at a time dog 49. Dog 49 is fixedly secured to rocker shaft 50. Rocker shaft 50 is suitably mounted at one end upon casing 1 and at its other end upon the gear casing 45. A finger 51 is fixedly secured on rocker shaft 50 (Fig. 4). A link 52 is connected at one end by a pin 53

5 to the upstanding finger 51 while its other end is pivotally connected at 54 to plate 55; this plate 55 is fixedly secured to the bottom of the vibrating classifier 12. Therefore when the operator turns the power shaft 43 gear 46 will rotate causing the spurs 48 to intermittently engage dog 49, swinging shaft 50 to the left a short distance which results in pulling the vibrating classifier to the left, against the action of springs 40. When the particular spur 48 passes off dog 49 springs 40 immediately pull the classifier 12 to the right, which is the cycle of the reciprocating movement of said classifier.

At the same time the rocker shaft is operated so is the blower, for the small cog-wheel 56, meshing with large gear 46, is rotated; gear 56 is mounted on shaft 57, which shaft is suitably supported upon the casing 1. A belt pulley 58 is driven by the rotation of the cog 56. Mounted on belt pulley 58 is a belt 59. Belt 59 is also mounted on a small belt pulley 60. Belt pulley 60 is fixed to shaft 61, Fig. 9, which shaft 61 carries the rotary fan or blower 37. Therefore it will be seen that when the power shaft 43 is rotated the blower 37 will be simultaneously operated, as well as the vibrating classifier 12.

In Fig. 12 the illustration represents an extra multiple concentrating table that may be used on certain occasions in operating the machine. This concentrating table would be used in the larger machines and in the more expensive machine where a more thorough recovery would be required, whereas the single concentrating table shown in Fig. 13 would be used in a less expensive machine. In Fig. 12 two condensers 18 are shown; Fig. 13 also shows two condensers 18.

In operation the material or ore to be tested is dumped into the hopper 4 and then the machine is started by the operator turning crank arm 44. The material is passed to the classifier 12 the quantity of the passing being controlled by the adjustment of the hinged hopper on the casing. The material spreads out on the upper deck 13 (Fig. 3) and is then fed to the classifier screen 14. The material that is small enough to pass through is subjected to a current of air under the deck and screen. The volume or power of this current of air is controlled by the valve device 32 hereinbefore described. The light material goes through with the air, while the heavier concentrate drops on the bottom of the classifier and is fed into a static condenser 18, the valuable concentrate passes through this condenser 18 into another air current and is classified into the two bins of drawer 28 formed by the partition 29, one bin being for the heavier, coarser concentrate, and the other bin for the finer, lighter concentrate. Now the material is fed by the table or bottom 17 to the static condenser 18, the lighter of this material is repelled by a pulsating air pressure that will not allow it to pass through the condenser and holds it static while it is floated off and over the static condenser into the tailings.

The larger material that will not pass through the classifier screen passes over the condenser and is dumped on the table below, where it is fed into the nugget-trap 22. All the heavier, valuable concentrate is retained in a lower compartment while the light, worthless material is fed onto a dump or tailings.

While I have described the preferred embodiment of this invention and illustrated the same in the accompanying drawings, certain minor changes or alterations may appear to one skilled

in the art to which this invention relates during the extensive manufacture of the same, and I, therefore, reserve the right to make such changes or alterations as shall fairly fall within the scope of the appended claims.

What I claim is:

1. In a machine of the class described, the combination with a casing provided with a top, of a vertical hopper provided with front and rear sides, said hopper having its lower end extending down through said top of said casing, a hinge secured to said top and to the rear side of said hopper, a stationary link secured to the side of said casing, a pair of links pivotally connected together, one of the links of said pair being pivotally connected to said stationary link, means pivotally connecting one of said links of the pair to the rear side of said hopper, said hopper provided with a horizontal flexible strip secured to the front side thereof, said flexible strip extending below the lower end of said hopper, a vibrating classifier provided with a deck, said classifier within said casing and below the lower end of said hopper, said flexible strip contiguous to said deck of the classifier, whereby the adjustment of said pivotally connected links will vary the position of said flexible strip with respect to the deck of said classifier, whereby the volume of material from said hopper on to said deck can be controlled, and manually operated means for imparting movement to said classifier.

2. In a machine of the class described, the combination with a casing, of a movable classifier in said casing provided with a flat discharge end, a nugget-trap for said discharge end, said nugget-trap comprising a frame provided with sides and with a screen-supporting transverse plate near its inner end, said sides being notched above said transverse plate, said discharge end of said

classifier engaging the top face of said transverse plate, and also positioned in said notches on the sides of said frame, and said frame provided with a central screen division and also with an upstanding screen-supporting portion near its outer end.

AZLE HERBERT UTLEY.
